CLAIM

The ornamental design for a door sweep, as shown and described.

DESCRIPTION

FIG. 1 is a left front perspective of my new design; FIG. 2 is a left side view thereof; the right side view being a mirror image thereof; FIG. 3 is a front view thereof; FIG. 4 is a rear view thereof; and, FIG. 5 is a bottom front perspective thereof.

The views of the door sweep not shown form no part of the claimed design. The dashed lines in the Figures immediately adjacent to the shaded areas represent unclaimed boundaries of the design. The dashed lines elsewhere in the Figures refer to environmental elements only and form no part of the claimed design. The wavy break lines in FIGS. 1 and 3-5 indicate indefinite length.
